DISPLAY DEVICE FOR ARTICLES OF
MERCANDISE

Harold L. Myers, Morristown, N. J.

Application May 20, 1939, Serial No. 274,725

3 Claims. (Cl. 206—44)

The invention relates to display devices for articles of merchandise and has for its object to provide a display device constructed in a novel manner to include one or more recesses dimensioned and shaped to accommodate the articles of merchandise for which the device is designed. The invention contemplates particularly a display device of maximum simplicity for displaying the article or articles of merchandise in an attractive manner and so as to be easily removable at will for purposes of sale and the like. Other more specific objects will appear from the description hereinafter and the features of novelty will be pointed out in the claims.

In the accompanying drawing, which illustrates an example of the invention without defining its limits, Fig. 1 is a perspective view of the novel device; Fig. 2 is a sectional view on the line 2—2 of Fig. 1; Fig. 3 is a cross-section on the line 3—3 of Fig. 1; Fig. 4 is a similar cross-section showing the device in a folded, flat condition, and Fig. 5 is a cross-sectional view illustrating the device in a partly completed condition.

The novel device comprises a single sheet of cardboard or other suitable material and consists of a front member 10 provided with at least one opening 11 of predetermined shape and dimensions dependent upon the articles of merchandise for which the device is designed, and preferably having a plurality of such openings 11 arranged in groups for instance as shown in Fig. 1, or otherwise as may be desired. In the illustrated example the openings 11 are of rectangular shape and dimensioned to accommodate rectangular articles of merchandise as exemplified for instance by conventional packages of safety-razor blades.

Main or outer spacing panels 12 are foldably connected with the front member 10, for instance, along opposite side edges thereof, in any convenient manner as by means of score lines 13. The main spacing panels 12 further are foldably connected with panel sections 14 and 15 respectively in any suitable manner as by means of score lines 16 extending in parallel relation to the score lines 13. In the finished device, the panel sections 14 and 15 have their free edge portions in overlapping surface engagement and fastened together in any conventional manner as by metallic staples 17 to constitute a rear member located in surface parallelism with the front member 10 in rearward registry with the one or more openings 11. An auxiliary or inner spacing panel 18 is foldably connected with the panel section 14 in any suitable manner as for instance by

means of a score line 19, and is itself foldably connected with a flap 20 for instance along a score line 21 or in any other equivalent manner; as shown in the drawing, the score lines 19 and 21 are parallel with each other and with the score lines 13 and 16. In the completed device the flap 20 lies in surface engagement with the inner face of the front member 10 and is secured thereto by means of metallic staples 22 or in any other convenient way. To facilitate the application of the staples 22 or their equivalent, the panel section 14 of the rear member may be provided at predetermined points with openings 23; it will be understood that the openings 23 correspond in number and location with the number and location of staples 22 used in a given device.

In its initial condition, the device consists of a blank cut and scored to provide the desired arrangement. To construct the device from the aforesaid blank, the flap 20 and auxiliary spacing panel 18 together are folded back on the score line 19 into surface engagement with the inside face of the panel section 14 as shown in Fig. 5. With the parts in their relation, the panel section 14 and the main spacing panel 12 with which it is foldably connected, are folded on the associated score lines 16 and 13 to bring the folded flap 20 and auxiliary spacing panel 18 into surface engagement with the inside face of the front member 10 as shown in Fig. 5. The staples 22 are then applied in registry with and through the openings 23 so as to pass through the flap 20 and front member 10 and thereby fasten said flap 20 to and in surface engagement with said front member 10 as illustrated in Fig. 5. The panel section 15 and the main spacing panel 12 with which it is foldably connected, are then folded on the associated score lines 13 and 16 to bring the panel section 15 into overlapping surface engagement with the panel section 14, as illustrated in Fig. 4. The staples 17 may then be applied through the openings 11 so as to extend through the overlapping portions of the panel sections 14 and 15; the latter are thereby fastened together to provide the rear member so that the device, at this stage, appears as shown in Fig. 4. In this folded condition said device is of compact flat form and accordingly may be readily stored and shipped in large numbers in a relatively small space.

To adjust the device to its unfolded operative condition, the main spacing panels 12 are folded, for instance, on the score lines 13, into upright approximately perpendicular relation to the front member 10. This adjustment of said panels 12

correspondingly adjusts the auxiliary panel 18 on the score line 21 and shifts the rear member consisting of the panel sections 14 and 15 into spaced surface parallelism with the front member 10 rearwardly thereof in registry with the openings 11 as shown in Figs. 1, 2, and 3. In this condition, the rear member constitutes a bottom for the opening or openings 11, as the case may be; the articles *a* when inserted into said openings 11 rest against said bottom and are accordingly securely held in place on the display device. The arrangement is such that the articles *a* when in place in the openings 11 project outwardly beyond the front member 10 as illustrated by dotted lines in Fig. 2; this result is attained by properly dimensioning the panels 12 and 18 relatively to the particular articles *a* for which a given device is designed, and enables said articles *a* to be readily removed at will for purposes of sale or the like.

The device may further include a panel 24 for displaying advertising matter, said panel 24 for instance, forming an extension of the front member 10 and being foldable relatively thereto on a score line 25. In the preferred arrangement the panel 24 is provided with an additional score line 26 in spaced parallel relation to the score line 25 as shown in Fig. 1. The score line 26 enables the panel 24 to be folded over the front member 10 and into surface engagement with the articles *a* as shown by dotted lines in Fig. 2, it being understood that the distance between the score lines 25 and 26 is approximately equal to the extent of projection of the articles *a* outwardly beyond the front member 10. With the described arrangement the panel 24 may be folded over the front member 10 or over and into contact with the articles *a*, as shown by dotted lines in Fig. 2; in this condition the device, whether empty or filled, is of compact form and is easily stored and shipped.

The device, with the articles *a* in place in the openings 11, may be maintained in display position in any conventional manner as by providing the panel 24 with a suspending eyelet 27 as shown in Fig. 1. The device may further include any other features commonly formed in corresponding types of display devices, as well as special features in addition to those shown in the drawing.

In all of its forms, the novel device is simple in construction and economical to produce and in its folded flat condition occupies a minimum of space and is readily stored and transported in small or large quantities. In its operative unfolded condition with the articles *a* in place, the device is also compact and easily handled.

Obviously the openings 11 may be otherwise shaped and otherwise grouped than illustrated in the selected example without in any way affecting the efficiency and purpose of the device.

Various changes in the specific forms shown and described may be made within the scope of the claims without departing from the spirit of the invention.

I claim:

1. A display device comprising a front member

provided with at least two spaced openings terminating at opposite edges of said front member and dimensioned and shaped to accommodate predetermined articles of merchandise, panel sections fastened together in overlapping surface engagement and located rearwardly of said front member in registry with the openings thereof, main spacing panels in permanent foldable connection with said front member along opposite edges thereof and with said panel sections along the respective outer edges thereof, an auxiliary spacing panel in permanent foldable connection with the inner panel section along the inner edge thereof, and a flap in permanent foldable connection with the auxiliary spacing panel and secured in surface engagement with the inner face of said front member, said spacing panels being pivotally movable in parallelism to shift the panel sections into spaced parallelism with said front member to constitute a common bottom for the openings therein and to provide a complete display body of tubular open ended form.

2. A display device comprising a front member provided with at least two spaced openings terminating at opposite edges of said front member and dimensioned and shaped to accommodate predetermined articles of merchandise, panel sections fastened together in overlapping surface engagement and located rearwardly of said front member in registry with the openings thereof, main spacing panels in permanent foldable connection with said front member along opposite edges thereof and with said panel sections along the respective outer edges thereof, an auxiliary spacing panel in permanent foldable connection with the inner panel section along the inner edge thereof, and a flap in permanent foldable connection with the auxiliary spacing panel and secured in surface engagement with the inner face of said front member, said spacing panels being pivotally movable in parallelism to shift the panel sections into spaced parallelism with said front member to constitute a common bottom for the openings therein and to provide a complete display body of tubular open ended form.

3. A display device comprising a front member provided with openings having their inner end in spaced registry with each other, panel sections fastened together at their inner edge portions in overlapping surface engagement rearwardly of said front member, main spacing members foldably connected with said front member and with said panel sections, and an auxiliary panel section foldably connected with the inner edge of said inner panel section and foldably connected with the inner surface of said front member in approximate registry with the inner end of one of said openings, said spacing members being pivotally movable in parallelism to shift the connected panel sections into spaced parallelism with said front member to constitute a common bottom for the openings therein and to provide a complete display body of tubular open ended form.

HAROLD L. MYERS.
